UNITED STATES PATENT OFFICE.

JAMES M. WILSON, OF NEWARK, NEW JERSEY, ASSIGNOR TO AMPLITONE COMPANY, INC., OF NEW YORK, N. Y., A CORPORATION OF NEW YORK.

TELEPHONE RECEIVER.

Application filed September 18, 1922. Serial No. 588,808.

The object of my invention is to improve the construction and operation of telephone receivers, and particularly those used in radio-telephony, whereby the sound reception is materially clarified, muffling and overtones eliminated and sound volume greatly increased, and it consists of placing a secondary diaphragm in close juxtaposition to the primary diaphragm, and separated therefrom by a non-metallic or elastic element located between their centers, so that when the two diaphragms are placed under a slight marginal compression, as by screwing down the cover cap, the centers of the diaphragms will be flexed out of their normal planes. It has been hitherto proposed to connect a pair of marginally clamped diaphragms with a rigid strut located at their centers; but I find that such a construction serves to magnify and emphasize some of the defects of a single diaphragm, and to impair the transmission of sound waves. Whereas, the inclusion of the slightly elastic or non-metallic element or member under the compression as hereinafter indicated, softens the metallic ring, eliminates overtones and materially increases the volume of sound transmission.

In the accompanying drawing, I have shown only so much of a well-known form of receiver as may be necessary to gain a full understanding of my improvement. In the drawing

Fig. 1 is a side elevation, partly in section of a receiver with my improvement included therein.

Fig. 2 is a plan of the secondary diaphragm.

Fig. 3 is a similar view of the primary diaphragm.

Fig. 4 is a diagrammatic section of the combined diaphragms showing their relative locations with respect to the receiver poles, but without compression.

Fig. 5 is a similar view, but showing the positions of the two diaphragms when under compression.

Fig. 6 is a side elevation partly in section of a modified form of receiver.

Figs. 7 and 8 are respectively top and bottom plans of the two diaphragms shown in Fig. 6.

Figs. 9 and 10 are respectively modified forms of the separating element permanently connected to the secondary diaphragm.

Similar reference numerals refer to like parts throughout the specification and drawing.

The receiver body or cup 1, the magnet system 2 and the talking circuit leads 3 are of the usual or of any preferred construction, and operate in the usual manner. The cover cap 4 is screwed down upon the threaded cup flange 5, and may be held in any adjusted position by the small set screw 6, passing through the cap flange and bearing upon the cup flange. The cap 4 has the internal ledge or shoulder 7, which bears upon the margin of the diaphragm. All of these parts are of the usual construction, except that the cap flange is made somewhat deeper, so as to provide for the extra depth of the two diaphragms when in place.

The metallic diaphragm 8 is slightly convexed, as shown in Fig. 4, and has a slight projection 9 at its center, which may be made by a center punch. In assembling, the diaphragm 8 rests upon the upper edge of the cup 1 with its convex side uppermost. The secondary diaphragm 10 is a plane disk, and may be either metallic or non-metallic. Excellent results have been obtained with secondary diaphragms made of mica, brass, aluminum, bronze, copper and thin sheet steel, among the metallic elements, and glass, celluloid, parchment, and shellac-impregnated paper among the non-metallic elements. So that the material is not important so long as it is of the proper thickness and has the requisite elasticity. At the center of the secondary diaphragm is a small cylindrically headed rivet 11, upon which the short section of tubing 12 is placed and held by friction. The secondary diaphragm is then placed upon the primary diaphragm 8, with the tube separator 12 over the projection 9, which serves to center the secondary, and finally the cap 4 is screwed down upon the cup 1 with the ledge 7 bearing upon and compressing the margin of the diaphragm. As the cap 4 is screwed down, the convexity of the primary diaphragm 8 is reduced and its center is pressed into close proximity to the poles of the magnet 2, and at the same time the secondary diaphragm 10 is convexed, as shown in Figs. 1 and 5.

The degree of this compression of the diaphragms is determined by the proximity of the center of the primary diaphragm to the magnet poles, which should be such

that with its maximum vibration the diaphragm should not actually contact the poles. In some cases, the convexity of the primary diaphragm is reduced to nothing, that is, the diaphragm is a plane disk; the pressure may even go further and depress the center until the convexity is reduced to a slight concavity, so long as the contact conditions are preserved. The adjustment is based upon the results obtained, the cap being screwed to that position where the greatest volume and clearest sound is transmitted.

In Fig. 6, I have shown a slight modification of the receiver cup 1' and cap 4', to provide for a secondary diaphragm 10' of larger diameter than the primary diaphragm 8'. The screw-threaded cup flange 5' is made larger to receive a correspondingly enlarged cap 4', within which is the ledge 7', bearing upon the margin of the enlarged secondary diaphragm 10'. A slight recess 13 is provided in the upper inner edge of the cup to receive the primary diaphragm 8'; the separating element 12' is located and secured in the same manner as heretofore described, and the adjustment is accomplished in the same manner.

I have found in practice that slightly better results are obtained in the way of clarity and volume, when the secondary diaphragm is made of some of the non-metallic materials and of a larger diameter than with both diaphragms of the same diameter.

The separator 12 or 12' may be attached to the secondary diaphragm in the manner above described, or it may consist of a small cup 14, with the rivet 15 passing through its bottom and secured to the center of the diaphragm, as shown in Fig. 9. Or it may be in the form of a rivet with a covered head, as shown at 16 in Fig. 10. When a slightly elastic or non-metallic separator is used, all trace of that metallic resonance so frequently present with and in a single receiver diaphragm seems to be eliminated, and the tone is clear and of increased volume, and the absence of muffling and overtones is at once apparent.

By the construction shown and described, I am able to accomplish very much improved results in the way of sound reception, even more than the simplicity of the device would seem to warrant or indicate.

It will be noted that the primary and secondary diaphragms are confined between the ledge 7 and the upper edge of the cup 1, with the member 12 separating them at the center, leaving the adjacent faces of the diaphragms free from compression. In the usual single-diaphragm receiver, it is customary to compress or confine the margin of the diaphragm between the ledge and the upper edge of the cup. This necessarily imposes the freedom of vibrational movement

of the diaphragm, for it permits the flexing of the diaphragm only within the unconfined area; that is, within the confined margin. This clamping of the margin must therefore produce undue mechanical stresses in the diaphragm, with a resulting damping of sound vibration.

The material from which the separator or spacing member 12, 12', 14, or 16, is made may be either soft or hard rubber, fiber, wood, or any non-metallic substance, all of which may be considered as elastic, or slightly yielding under pressure.

I am aware that it has been proposed to provide a receiver with two diaphragms held apart by a rigid spacing member, but I believe that I am the first to use a plane secondary and a convex primary diaphragm, with a non-metallic or elastic spacing member between them, together with means for flexing the secondary into convex form and the primary into a substantial plane, and I therefore desire to claim such a construction as broadly as the scope of my invention will permit.

I claim:

1. In a telephone receiver, the combination of a normally convex primary diaphragm, a normally plane secondary diaphragm, a spacing member located at and separating the centers of said diaphragms, a receiver cup, a cover cap therefor, and means upon said cup and cap for pressing the circumferences of said diaphragms toward each other, whereby the convexity of said primary diaphragm is reduced and said secondary diaphragm is made convex.

2. In a telephone receiver, the combination of a plane diaphragm, a convex diaphragm, a spacing member between the centers of said diaphragms, and means for applying pressure upon the non-adjacent faces of said diaphragms at their margins to flex the same toward each other, whereby said plane diaphragm is made convex and said convex diaphragm is made plane.

3. In a telephone receiver, the combination of a plane diaphragm, a convex diaphragm, and a spacing member between their centers, and means pressing their margins together to convex said plane diaphragm and reduce the convexity of said convex diaphragm.

4. In a telephone receiver, the combination of a receiver cup and a cover cap therefor, with a convex primary diaphragm, a plane secondary diaphragm, a spacing member between the centers of said diaphragms, and means upon said cup and cap for pressing the circumferences of said diaphragms toward each other to change said secondary diaphragm to convex and reduce the convexity of said primary diaphragm.

5. In a telephone receiver, the combination of a pair of diaphragms of different

- diameters, a spacing member located between the centers of said diaphragms, and means applied to the circumferences of said diaphragms to flex the same toward each other.
6. In a telephone receiver, the combination of a receiver cup and a cover cap therefor, a primary diaphragm and a secondary diaphragm, a spacing member located centrally of and yieldingly separating said diaphragms, and means for clamping said diaphragms between said cap and cup whereby said diaphragms are flexed from their normal planes.
7. In a telephone receiver, the combination of a primary diaphragm and a secondary diaphragm a spacing member yieldingly separating said diaphragms at their centers, and means for placing the margins of said diaphragms under slight compression to flex them from their normal planes.
8. In a telephone receiver, the combination of a pair of juxtaposed diaphragms, a non-metallic spacing member located between the centers of said diaphragms, a receiver cup and a cover cap therefor, and means upon said cup and cap bearing upon the non-adjacent margins of said diaphragms for flexing the same toward each other.
9. An instrument for translating electrical undulations into sound vibrations comprising in combination, a pair of centrally spaced diaphragms, means engaging said diaphragms adjacent their peripheries and flexing said diaphragms, the distance between the center of one of said diaphragms and said last named means being greater than the corresponding distance between the center of the other diaphragm and the said last named means, and means including an electromagnet for vibrating said diaphragm, one of said diaphragms being located between said electromagnet and the other diaphragm.
10. A device of the class described comprising in combination, a casing, a cap adjustable toward and away from said casing, an electromagnet mounted in said casing, and a pair of centrally spaced diaphragms mounted between said electromagnet and cap, said diaphragms being of different effective diameters, and means upon said casing and caps for engaging the non-adjacent margins of said diaphragms and flexing the same toward each other upon movement of said cap toward said casing.
11. A device of the class described comprising in combination, a casing, a cap adjustable toward and away from said casing, an electromagnet mounted in said casing, and a pair of centrally spaced diaphragms mounted between said electromagnet and cap, said diaphragms being of different effective diameters, means upon said casing and cap for engaging the non-adjacent margins of said diaphragms and flexing the same toward each other upon movement of said cap toward said casing, and means for locking the cap and casing in various positions of relative adjustment.
12. An instrument for translating electrical undulations into sound vibrations comprising in combination, a disc-shaped primary diaphragm and an electromagnet of which said diaphragm constitutes the armature, a secondary diaphragm located on the side of said primary diaphragm remote from said electromagnet, means spacing said diaphragms substantially at their centers, and means engaging said diaphragms adjacent their peripheries for flexing said diaphragms toward each other.
13. The instrument set forth in claim 12 in which the secondary diaphragm is constructed of a different material than that of the primary diaphragm.
14. The instrument set forth in claim 12 in which the secondary diaphragm is constructed of non-metallic material.
15. The instrument set forth in claim 12 in which the two diaphragms are of different effective diameters.
16. The instrument set forth in claim 12 in which the secondary diaphragm is constructed of non-metallic material and is of greater effective diameter than the primary diaphragm.

JAMES M. WILSON.
